UNITED STATES PATENT OFFICE

HEINRICH SCHWARZ, OF LAZY, CZECHOSLOVAKIA

COKE-OVEN DOOR

Application filed March 22, 1927, Serial No. 177,451, and in Czechoslovakia March 26, 1926.

In order to avoid the tedious and costly process of sealing the doors of coke furnaces with clay or the like, various constructions for hermetically-closing self-sealing doors have been proposed. The practical introduction of these constructions has hitherto failed on account of the high cost and the short life of the packing material used.

The object of the present invention is to entirely avoid the employment of dear packing material, such as asbestos or the like, and by means of a suitable construction of the door frame and of the door of the furnace itself, to prevent the gases escaping on account of their expansion during the process of producing the coke.

The characteristic feature of the invention consists in that between the furnace door itself and the frame of the door one or more completely closed but separate hollow spaces are provided, in which the emerging gases are expanded, whereby they are prevented from escaping.

In the accompanying drawing the object of the invention is shown by way of example. Fig. 1 shows a longitudinal section through the furnace door, Fig. 2 a cross section on the line *a*—*b* of Fig. 1, and Fig. 3 shows a slight modification of the construction illustrated in Fig. 2.

The construction comprises a frame 1 surrounding and extending round the door aperture in the furnace chamber 2 and the actual door 3 of the coke furnace.

The frame 1 is provided on its external side 4 with suitable recesses, grooves or channels 5 or the like. The door 3 is formed as a plug door and is provided on the face adjacent the furnace chamber with ribs or corrugations 6, which engage hermetically in the recesses, grooves or channels 5 or the like of the frame 1. When the door 3 is closed it forms together with the frame 1 a hollow space 9, in which the gases escaping from the furnace chamber 2 through the first packing surface 7 can expand, and these gases are prevented from further escape by the hollow spaces 8, formed between the ribs 6 and the recesses 5, or by the recesses 5 alone, which spaces form as it were a labyrinth.

The ribs 6 may, of course, be provided in the frame 1 and the grooves 5 in the door. Moreover, the ribs 6 may be omitted or be provided in the door 3 only or the grooves 5 may be provided in the frame 1 alone. (Fig. 53.) These grooves 5 may be disposed exactly opposite one another or laterally disposed to one another and can have any desired shape or construction.

The present self-sealing and hermetically closing door for coke furnaces has the advantage over all other self-sealing hermetically closing doors, that a complete and reliable action is assured and that the slightly increased cost of construction is compensated in a short time by the savings made in running and upkeep costs.

The number of the hollow spaces 8, as also the shape and construction of the same, or of the paths of the labyrinth so formed, are chosen according to the size of the furnace and the pressure produced therein.

I claim:—

In a self-sealing coke oven closure means, the combination with a door frame having a continuous groove on the face adjacent the furnace chamber, and a plurality of continuous grooves on the face farthest from the furnace chamber; of a door having direct contact with said frame and provided with ribs fitting in said last named grooves, said door and frame being formed to provide anular cavities lying between them to successively receive gases escaping from the oven chamber.

In testimony whereof I affix my signature.

DR. ING. HEINRICH SCHWARZ.
